R. C. STUBBS

MEASURING DEVICE FOR STREET AND ROAD PAVING AND THE LIKE

Filed Sept. 24, 1924

FIG. 1.

Patented Aug. 9, 1927.

1,638,715

UNITED STATES PATENT OFFICE.

ROBERT C. STUBBS, OF DALLAS, TEXAS.

MEASURING DEVICE FOR STREET AND ROAD PAVING AND THE LIKE.

Application filed September 24, 1924. Serial No. 739,703.

My invention relates to road or street building equipment and more particularly to measuring devices for securing uniform amounts of ingredients for making concrete or other plastic and for securing uniform amounts of the mixed material for spreading on the street or road; and the object is to provide simple measuring devices for operation with bins or hoppers which contain material so that uniform amounts of ingredients and uniform amounts of mixed material may be secured and to provide means for varying the capacity of the measuring devices as may be required, that is, means for increasing or decreasing the amount of material as may be required. The handling of sand, stone or pebbles, or cement has been largely accomplished by transporting such materials from the supply sources in wheel barrows or trucks which are loaded by workmen using shovels. Such handling is not uniform for many reasons. My device as proposed for protection against carelessness and fraud in such work has been demonstrated to be absolutely accurate and invaluable to the end that correct proportions and amounts of material are insured in such manner that it would be impossible for a different amount of material to be obtained in any volume of different batches so measured. The same measuring device may be used when the mixed concrete is to be transported from the mixer to a street or road where it is to be laid so that the thickness of the concrete will be uniform. Other objects and advantages will be fully explained in the following description and the invention will be more particularly pointed out in the claims.

Reference is had to the accompanying drawings which form a part of this application.

Fig. 1 is a front elevation of two hoppers or bins and measuring drums therefor, partly in section. Fig. 2 is a section in perspective of a hopper and the measuring drum and the means for varying the cubical capacity of the drum. Fig. 3 is an end elevation of the machine. Fig. 4 is a transverse section of the drum and the means for varying the cubical capacity of the drum on a larger scale. Fig. 5 is a broken longitudinal section of the same. Fig. 6 is a perspective view of the device for varying the cubical contents of the drum or drums.

Similar characters of reference are used to indicate the same parts throughout the several views.

A portable bin or hopper is herein set forth, and it may be preferable to make a double bin or hopper and drum because the two sets of double equipment can be more economically constructed together than it would be to build two separate structures. An upright frame is provided with supports or posts 1, 2, and 3 to which are attached beams 5 and 6. The frame may be complete by cross-beams 4, 7, 8, and 9, which are attached to the uprights 1, 2, and 3. The beams 5 and 6 may be extended to form handles 10, for convenience in moving the devices from place to place.

A double hopper 18 is mounted on the frame and provided with a divider 17 at the central portion for directing material to the measuring drums or receptacles 11 and 12. The drums 11 and 12 are cylindrical structures with openings 15 in their upper sides to receive material from the hoppers. The drums may be independently operated. The drum 11 is provided with stub shafts 19 which are rigid therewith to be journaled in the cross-beams 7 and 8 and the drum 12 is provided with stub shafts 20 which are to be journaled in the cross beams 8 and 9. The drums 11 and 12 may be revolved by any suitable gearing. Ratchet wheels 21 are rigidly mounted on the shafts 19 and 20 and levers 22 are pivotally connected to the shafts 19 and 20 and provided with pawls 23 on levers 22 for operating the wheels 21. The hoppers 18 have curved flanges 24 on their lower edges to form sealing devices with portions 25 of the drums 11 and 12 which as shown are not cut away at the ends.

Each drum, 11 and 12, may be divided into two compartments, as shown in Figs. 2 and 4. Two openings 15, one for each compartment, are formed for receiving and discharging material. The drum 11 is divided by a diametrical partition, making two compartments 11 and 11'. There may be different means of accomplishing this. The drawings show that the metal 26 and 27 which forms the peripheral wall extends from one opening 15 to the other opening 15. The metal is then bent inwardly to form the partition members 26' and 27' which meet at the longitudinal center of the drum. It is apparent that the members 26-27 and 26'-27' may

be one piece of metal. The partition members must be rigid with the members 26 and 27 which are attached to the end members 28 of the drum.

5. Means are provided for varying the cubical capacity of the compartments 11 and 11'. Divider partitions 28 and 29 are mounted rigidly on disks 30 and 31 and the disks 30 and 31 are revolvably mounted on the stub shafts 19 and 20. The divider partitions 28 and 29 may be turned to any required position within the compartments 11 and 11' to increase or decrease the cubical capacity of these compartments. The disk 31 has an 10 aperture 32 and the adjacent drum head 28' has a plurality of apertures 33. A pin 34 may be used to fix the disk 31 in whatever position that may be required. The disk 31 will be revolved to bring the aperture 32 15 to the aperture 33 which is required and then a pin 34 inserted into the head 28' and into the disk 31 to fixedly position the disk 31 to the head 28 and consequently fix the dividers 28 and 29 in position so that the 20 compartments 11 and 11' will contain the required amount of material.

Yielding cut-offs 35 are attached to the hoppers 18 to prevent surplus material from following the discharge openings 15. The 30 yielding cut-offs may consist of steel brushes. In order to prevent material from falling out of the drums prematurely, guards 36 are placed back of the drums and curved downwardly as shown.

35. In order to let any trash or loose material out of the drums which may accumulate between the members 27' and 29 and between members 28 and 26' apertures 37 are made in the disks 30 and 31 and apertures 38 are 40 made in the heads 28' for removal of any such accumulations.

What I claim, is,—

45. 1. A measuring device for street and road paving and the like comprising a revoluble cylindrical receptacle, a longitudinal diametral partition dividing said receptacle into compartments, each compartment having an opening for receiving and discharging material, means within each compartment for varying the cubical capacity thereof consisting of a pair of disks revolvably mounted in said receptacle, means for fixedly connecting said disks to the ends of said receptacle, and dividers rigid with said disks, and 50 means for revolving the receptacle.

60. 2. A measuring device for street and road paving and the like comprising a revoluble receptacle, a longitudinal diametral partition dividing said receptacle into compartments, each compartment having an opening for receiving and discharging material,

dividers, one in each compartment, for varying the cubical capacity of the compartments, means for fixing said dividers in different positions within said compartments 65 consisting of revoluble disks rigid with said dividers and means for fixedly connecting said disks to the ends of the said receptacle, and means for revolving said receptacle.

3. A measuring device for street and road paving and the like comprising a revoluble cylindrical receptacle having flat heads closing the ends thereof, a longitudinal diametral partition dividing said receptacle into compartments, each compartment having an opening for receiving and discharging material, revoluble disks within said receptacle adjacent to said heads, dividers, one for each compartment, rigid with said disks, for varying the cubical capacity of said compartments, and means for revolving said receptacle.

4. A measuring device for street and road paving and the like comprising a supporting frame, a feed hopper mounted on said frame and provided with a discharge opening, a cylindrical receptacle journaled in said frame, a diametral partition dividing said receptacle into compartments, each compartment having an opening for receiving and discharging material adapted to register with said hopper discharge opening, means within each compartment for varying the cubical capacity thereof consisting of revoluble disks and dividers rigid 90 therewith and means for fixedly connecting said disks to the ends of said receptacle, and means for revolving said receptacle.

5. A measuring device for street and road paving and the like comprising a supporting frame, a feed hopper mounted on said frame and provided with a discharge opening, a cylindrical receptacle journaled in said frame, a fixed diametral partition in said receptacle dividing the same into compartments, each compartment having an opening for receiving and discharging material adapted to register with said hopper discharge opening, movable dividers, one in each compartment, for varying the cubical 100 contents of the compartments, means for fixing said movable dividers at different positions in said compartments consisting of revoluble disks rigid with said dividers and means for fixedly connecting said disks to 105 said receptacle, a guard for preventing the spreading of material discharged from said compartments, and means for revolving said receptacle.

In testimony whereof, I set my hand, this 120
18th day of September, 1924.

ROBERT C. STUBBS.
